UNITED STATES PATENT OFFICE.

THEODOR KOCH AND KURT K. LEDIG, OF NEWARK, NEW JERSEY, ASSIGNEES TO AMERICAN PLATINUM WORKS, OF NEWARK, NEW JERSEY, A CORPORATION OF NEW JERSEY.

PERFORATION-CLEANSING RECIPROCATING-BRUSH APPARATUS.

Application filed October 11, 1922. Serial No. 593,677.

To all whom it may concern:

Be it known that we, THEODOR KOCH, a citizen of Germany, residing at Newark, in the county of Essex and State of New Jersey, and KURT K. LEDIG, a citizen of the United States, also residing at Newark, in the county of Essex and State of New Jersey, have invented certain new and useful Improvements in Perforation-Cleansing 10 Reciprocating-Brush Apparatus, of which the following is a specification.

This invention relates to devices for mechanically cleaning a plurality of fine perforations, in a thin plate, metallic gauze or 15 like article, without damaging the same or enlarging the area of the openings or interstices.

While the apparatus hereafter disclosed is broadly applicable to a considerable range 20 of articles, as gratings, gauzes, perforate plates, etc., irrespective of the shape of the openings or how closely they may be arranged, the original purpose of the invention is to cleanse the openings in the end 25 wall of an appliance technically known as a spinneret, used for extruding exceedingly minute filaments or threads of the viscous substance used in making artificial silk.

This substance or composition, in a semi- 30 liquid or jelly like condition, is forced under great pressure into a thin walled annulus having a plurality of minute circular openings disposed in equal spaced relation in its flat bottomed wall, the extruded plastic filaments hardening almost at once in the air 35 due to the volatilization of the liquid constituents of the mass.

Notwithstanding care in preparing the ingredients and mixing the mass, occasionally 40 a small not properly incorporated particle will obstruct one of the passages, which are approximately .004 of an inch in diameter, one of the threads may congeal too rapidly, or other causes arise which compel cleansing 45 of the fine orifices.

This operation entails removal and substitution of the spinneret, and, in view of thinness of the wall, the small diameter of the hole and that it must be essentially cylindrical, ordinary methods of cleaning cannot 50 be safely used; a brush having fine but stiff bristles directed lengthwise against the perforate wall is considered the only safe method, the brush being used dry or mois-

tened with a solvent for the substance as may 55 be preferred.

Thus one of the objects of the invention is to provide an apparatus suited to engage a removable brush and to rapidly move the same in the direction of length of its bristles 60 reciprocatively.

Another purpose is in the provision of means for adjustably supporting the perforate articles in register with the brush and for readily interchanging the articles. 65

A further aim is to provide a support capable of receiving a plurality of the articles to be cleansed and associate therewith means for automatically and intermittently advancing the same within the scope of brush 70 action.

These and other related objects are attained by the novel construction and combination of parts hereinafter described and shown in the accompanying drawings, forming a material part of this disclosure, and in which:—

Figure 1 is a plan view of an apparatus made in accordance with the invention.

Figure 2 is a side elevational view of the 80 same.

Figure 3 is a front elevational view thereof.

Figure 4 is a plan view showing a modification in holder structure. 85

Figure 5 is a partial side, partial sectional view of the modification.

Figure 6 is a perspective view of the spinneret drawn to an enlarged scale with the 90 perforations exaggerated.

In these drawings the numeral 15 designates an elongated rectangular flat base plate, on one portion of which is secured an electric motor 16.

Bolted to the opposite end of the base are 95 the feet 17 of an arched column 18 having at its center a raised upright 19 terminating in opposed outstanding flanges 20 and surrounded by a removable cap 21.

An outstanding lug 22 extends to the 100 front from one of the members of the arched column and a similar but thinner lug 23 projects in like manner from the other member.

A stud 24 is rigidly set in the lug 22 to 105 extend upward and rotatably mounted on the stud is a hub 25 formed with a plate lever 26 adapted to engage the upper sur-

face of the lug 23, the lever being notched, as at 27 to receive the body of a screw 28, the head of which acts as a retainer for the lever.

5 The upright 19 contains a cylindrical bore 29 in which operates a plunger bar 30 having a flattened portion 31 to which is secured the base element 32 of an outstanding forked bracket 33, said base extending laterally outward to ride upon the recessed edges of a cutaway portion 34 of the upright, the base preventing rotation of the plunger 30 and limiting its motion.

15 A coiled compression spring 35, enclosed in the upper end of the bore 29 abuts the top of the plunger and cap 21 respectively, tending to force the plunger downwardly and an opening 36 in the cap 21 permits air to freely pass besides admitting a lubricant to the plunger.

20 The lower end of said plunger extends below the arch of the column and has secured to it a fork 37 carrying a pin on which is rotatably mounted a roller 38.

25 This roller rests upon the peripheral surface of a cam 39 attached rigidly to the shaft 40 of the motor 16 thus giving a reciprocating movement to the plunger 30 and forked bracket 33 in which is removably engaged a brush 41 the bristles 42 of which are directed vertically downwardly.

30 The lever 26 contains a screw threaded opening 43 receptive of a stem 44 provided with clamp nuts 45 below the lever and formed with a head 46 flattened upon opposite sides, as at 47 to receive a wrench, said head having an annular shoulder 48 from which extends a projection 49 suited to engage the spinneret 50.

35 Said spinneret, shown in detail in Fig. 6 consists of a thin walled cylinder formed with a concentric flange 51 adapted to rest on the shoulder 48 while the projection 49 reaches partially into the cylinder to center and support the same.

40 Formed at the top of the cylinder is a flat cover plate 52 containing a plurality of perforations 53 approximately .004 of an inch in diameter.

45 As has been seen, the spinnerets are movable directly under the axis of the brush 41 which is moved reciprocatively at a high rate of speed, its bristles 42 entering the perforations of the spinneret and forcing accumulations into the space at the top of the element 49, the action of cleaning being very rapid and thorough, while the time of changing from one spinneret to another is negligible.

50 In the modification shown in Figs. 4 and 5, the latch lever 26 is omitted and in its place is a turn-table 60 fixed on the end of a vertical shaft 61 rotatably mounted in a foot bearing 62 secured on the base 15.

55 Said turn-table is arranged with equally

spaced peripheral openings to receive the stems 44 and associated parts which support the spinnerets and is provided with a notched disc 63 midway in its height.

60 Fixed on the motor shaft is a friction pulley 64 in peripheral engagement with a larger wheel 65 carried rigidly on the end of a horizontal shaft 66 revolvably mounted in a pedestal 67 on the base 15, said shaft having a pin 68 fixed in its opposite end 70 engaging the teeth of the notched disc 63 and advancing it intermittently so as to bring the spinnerets into axial alignment with the brush.

75 In order to avoid over rotation of the shaft 61, a spring pressed brake 69 is arranged in the foot bearing 62, and obviously any reasonable proportion of friction wheels or gears may be used for rotating the turn-table at the speed desired.

80 In this modification the work of clearing the spinnerets is substantially continuous, those which are treated being removed and replaced by others in a clogged condition without cessation of operation.

85 While the foregoing is descriptive of cleansing a specific article it will be apparent that the structure can be arranged for operating on other articles by slight changes which do not include invention, being merely 90 mechanical details.

95 The foregoing disclosure is to be regarded as descriptive and illustrative only, and not as restrictive or limitative of the invention, of which obviously an embodiment may be 100 constructed including many modifications without departing from the general scope herein indicated and denoted in the appended claims.

105 Having thus described our invention, what we claim as new and desire to secure by Letters Patent, is:—

110 1. An apparatus for cleansing the apertures in a perforate article comprising a reciprocating carrier, a cylindrical brush removably engaged lengthwise in said carrier presenting downwardly extending bristles a support on which the article is removably engaged to register with the bristles of said brush, and means for adjusting said support.

115 2. An apparatus for cleansing the apertures in a perforate article comprising a slide, a brush carried lengthwise by said slide, an article holder registerable with said brush, means for adjusting the relative distance between said holder and brush, positive means for intermittently actuating said slide to move the brush away from the article, and resilient means for returning the slide whereby the brush is brought against the article to enter the perforations there-in.

120 3. An apparatus for cleansing the apertures in a perforate article comprising a 130

base, an arched column thereon, having a central raised, bored extension, a spring pressed slide operable in said extension, a motor on said base, the shaft of said motor reaching into the space in the arched column, a cam on the shaft, a roller carried by said slide engaging said cam, a bracket 25 fixed to said slide, said bracket having an outstanding fork, a brush removably engaged in the fork, a turn-table, article supports adjustable on said turn-table, said supports being registerable with the axis of 30 said brush, and means for intermittently actuating said turn-table, said means being driven by said motor.

5 reaching into the space in the arched column, a cam on the shaft, a roller carried by said slide engaging said cam, a bracket fixed to said slide, said bracket having an outstanding fork, a brush removably engaged in the fork, a latch lever pivoted at one end to one of the elements of said column, said lever engaging the other element of the column, and an article holding support adjustably engaged in said lever,

10 15 said support being registerable with the axis of said brush.

4. An apparatus for cleansing the apertures in a perforate article comprising a base, an arched column thereon, having a central raised, bored extension, a spring

pressed slide operable in said extension, a motor on said base, the shaft of said motor reaching into the space in the arched column, a cam on the shaft, a roller carried by said slide engaging said cam, a bracket 25 fixed to said slide, said bracket having an outstanding fork, a brush removably engaged in the fork, a turn-table, article supports adjustable on said turn-table, said supports being registerable with the axis of 30 said brush, and means for intermittently actuating said turn-table, said means being driven by said motor.

This specification signed and witnessed this 10th day of October, 1922.

THEODOR KOCH.
